ELECTRIC CAR HEATER

George F. Wennagel and Carroll Thomas, Baltimore, Md.

Application June 17, 1927. Serial No. 199,574

15 Claims. (Cl. 219—34)

The invention relates to electric car heaters. The principal object of the invention, generally stated, is to provide a car heater adapted to be mounted beneath the seats and to be supported 5 in part by the seat pedestal, the device performing the double function of serving as a heater and as a foot rest.

An important object of the invention is to provide a car heater particularly well adapted for 10 use in connection with the car heating system disclosed in our co-pending application for patent for Car heating apparatus, filed April 1st, 1926, Serial No. 99,137, there being, however, no limitation as to the employment of the present 15 device as part of said system inasmuch as it could be used in connection with some other system.

Another object of the invention is to provide 20 a car heater having a novel ground connection whereby the current will be carried off to the car trucks in the event of a short circuit within the heater so that injury to the passengers will be avoided, the ground connection forming a part of the device itself.

25 A more specific object of the invention is the provision of a heater so constructed as to be capable of application to or mounting upon the pedestals of seats of different lengths, it being consequently possible to effect installation in 30 already existing railway equipment without any particular difficulty.

Still another object is to provide a heater which preferably has a heating unit cast or molded into the heat radiating shell to avoid losses as the 35 result of poor mechanical contact, the specific unit being conveniently constructed in accordance with the disclosure in our co-pending application for patent filed June 17, 1927, Serial No. 199,577.

40 An additional object is to provide a heating device of this character which will be simple and inexpensive to manufacture, easy to install, positive in action, efficient and durable in service, and a general improvement in the art.

45 With the above and other objects and advantages in view, the invention preferably consists in the detailed construction and the arrangement and combination of parts to be hereinafter more 50 fully described and claimed, and illustrated in the accompanying drawings in which:

Figure 1 is a top plan view of the device, with parts in section, showing it in mounted position with respect to a portion of a car and a seat 55 pedestal,

Figure 2 is a cross section taken on the line 2—2 of Figure 1,

Figure 3 is a cross section on the line 3—3 of Figure 1,

Figure 4 is a fragmentary vertical section taken 60 on the line 4—4 of Figure 1, and

Figure 5 is a detail section through the ground clamp taken on the line 5—5 of Figure 1.

Referring more particularly to the drawings, the numeral 1 designates a portion of the side, 2 65 the floor line and 3 a seat pedestal which, as is well known, is generally of a hollow shell-like construction though, as a matter of fact, there is no particular limitation as to this detail inasmuch as the heater to be described might just as readily be mounted upon a seat pedestal of an entirely different type. In cars of more modern types there is usually provided a channel, housing or conduit 4 at the juncture of the side or wall with 70 the floor for the purpose of enclosing the conductors which feed current to whatever heaters are used or to any other devices forming part of the car equipment, the housing or conduit being generally lined with asbestos or other non-inflammable material 5. However, no novelty 80 is claimed up to this point.

In carrying out the present invention we provide a bracket or end member 6, formed conveniently as a casting, disposed against the side 85 of the car or against the conduit or housing and secured thereto as by means of screws or bolts 7 located at any desired points, it being preferable that sheets of asbestos or the like indicated at 8 be interposed between the bracket and the side 90 wall or housing for the purpose of preventing conduction of excessive heat to the latter. Near its ends the bracket is shown as formed or otherwise provided with sockets 9 within which are engaged the ends of elongated foot rest members 10 which 95 may, in actual practice, be formed simply as lengths of pipe having their other ends closed by caps, plugs or the like indicated at 11. The members 10 pass slidably through T's or their equivalent, as shown at 12, these T's being, in turn, carried by a transverse member 13, which may also be a pipe, extending through suitable openings 14 in the seat pedestal 3. In view of the fact that the members 12 are slideable with respect to the members 10 it is clear that installation of the device may be readily effected beneath seats of different lengths, that is to say, regardless of the distance between the seat pedestal and the side of the car. Obviously, in the assembly of the parts it will be necessary that the member 13 be in- 110

serted through the seat pedestal and connected with the T's 12 prior to the placing of the members 10 in position. Any desired means may be provided for holding the parts against subsequent dis-
5 placement. While the above described parts are shown as consisting of pipe sections and fittings it should be distinctly understood that anything of an equivalent nature may be used though these elements are highly satisfactory on account
10 of their simplicity and for the additional reason that the cost thereof is slight. The members 10 not only serve as foot rests but cooperate with the parts 12, 13 and 14 to form a portion of the supporting frame for the heater to be described, the
15 frame structure further including a bar 15 bridging the space between the members 10 and extending through openings 16 in the confronting portions thereof, the bar terminating in reduced extensions 17 fitting within sockets 18 in the outer portions of the members 10. Notwithstanding the disclosure, an alternative structure embodying these same general characteristics may be provided.
20 The heater itself is indicated generally at 19 and preferably comprises a metal shell 20 located between the bracket 6 and the bar 15. Extending axially through the shell is the heating unit indicated as a whole by the numeral 21 and this heating unit may embody the details disclosed in
25 the above mentioned co-pending application filed June 17, 1927, Serial No. 199,576 and preferably has the radiating shell cast directly thereon as set forth in the above mentioned co-pending application filed June 17, 1927, Serial No. 199,577, though it is conceivable that modifications in these particulars may be resorted to. It should be mentioned in passing that the shell 20 is provided with any suitable number of outstanding
30 vanes 22 for the purpose of increasing the radiating surface.

The heating unit is disclosed as comprising an elongated metal tube 23 which has one end projecting beyond the shell 20 and secured with respect to the bar 15 by means of a saddle or clamp 24 located beneath the bar 15 and secured thereto as by bolts and nuts 25 and 26 respectively though other securing means could be employed if desired. The other end of the tubular member
35 23 carries a cuff 27 which is externally threaded and screwed within a threaded boss 28 which projects from the bracket or end member 6. The tube 23 contains a suitable resistance element 29 here shown as wound upon a core 30 and embedded within a mass 31 of material such as magnesium oxide which acts to conduct the heat to the shell and which also acts to hold the resistance coil in place and prevent vibration thereof. At the second mentioned end of the tubular member 23 there is preferably provided an insulator 32 through which extend the terminals 33 which connect the resistance coil with the feed cables 34 located within the box or casing 4, another insulator 35 being provided in the wall of this housing or box where the cables pass therethrough. The space between the insulators 32 and 35 is preferably filled with some insulating and sealing compound indicated at 36.

An important feature is the provision of means
70 for grounding the heater so that in case of a short circuit the current will be conducted away to the car trucks and injury to passengers prevented. In the carrying out of this detail it is intended that all of the heaters in a car be connected with a conductor 37 which may extend

entirely around the car and which may be connected with one or more trucks at any desired number of points. At each heater the conductor 37 is accommodated within a groove 38 in the lower portion of the bracket 6 and is secured therein by means of a clamping plate 39 provided with a rib 40 entering the groove and engaging the conductor 37. The clamping action is effected by means of suitable cap screws 41 or the like. While it is not essential, it may be preferable to provide a strip or block 42 of insulating material located between the bracket 6 and the floor of the car. Molding 43 may be provided to enclose the conductor 37.

Assuming that the installation has been made as above described and as shown, it will of course be apparent that the heater will act in substantially the same manner as any other heater of the resistance type, the heat generated by the resistance of the coil 29 to the flow of current therethrough being communicated by the packing 31 and tubular member 23 to the shell 20 where radiation occurs. The members 10 serve as foot rests for the convenience of the passengers of the car and owing to their provision it is apparent that there will be no necessity and probably no possibility of placing their feet upon the radiating shell with possible detriment to their footwear. It is really believed that the construction, operation and advantages will be readily apparent to one skilled in the art without further explanation.

While we have shown and described the preferred embodiment of the invention it should be understood that the disclosure is merely an exemplification of the general features involved and that the right is reserved to make all such changes in the details of construction and also the combination and relation of parts as will not depart from the spirit of the invention or the scope of the claims hereunto appended.

Having thus described the invention, we claim:

1. In a car heater, the combination with a seat and its pedestal and with a metallic member at the side of the car, of an electric heater located beneath the seat and having one end carried by the pedestal and its other end carried by said member the heater including a heat radiating member having a heating unit therein and further including longitudinally extending foot rests located at opposite sides of and spaced from the radiating member.

2. In a car heater, a bracket mounted at the side of the car beneath a seat, a frame carried by the bracket and connected with the seat pedestal, a heat radiating member mounted within the frame, and a heating unit within the radiating member, the frame including foot rests located at opposite sides of the radiating member.

3. In a car heater, a bracket mounted at the side of the car beneath a seat, a frame carried by the bracket and connected with the seat pedestal, a heat radiating member mounted within the frame, and a heating unit within the radiating member, the frame including foot rests located at opposite sides of the radiating member and being adjustable longitudinally for mounting beneath seats of different lengths.

4. In a car heater, a supporting member mounted beneath a seat and against the side of a car, a frame carried by said supporting member and including spaced foot rests and a transverse element connecting the same and extending through the seat pedestal, a radiating mem-

- ber carried by the frame and extending axially thereof, a heating unit within the radiating member, and a ground connection secured to the supporting member.
5. In a car heater, a supporting member mounted beneath a seat and against the side of a car, a frame carried by said supporting member and including spaced foot rests and a transverse element connecting the same and extending through the seat pedestal, a radiating member carried by the frame and extending axially thereof, a heating unit within the radiating member, and a ground connection secured to the supporting member including a clamping plate, the supporting member having a groove receiving a conductor held by the clamp. 80
10. In a car heater, a metallic support disposable against the side of a car beneath a seat, foot rests carried by said support, a transverse member slideable along said foot rests and extending transversely through the seat pedestal, a transverse bar bridging and connected with the foot rests, a radiating member, a heating unit extending axially through the radiating member and projecting beyond both ends thereof with one end secured to the support and its other end supported by the bar, the heating unit embodying a tubular metal case united to the radiating member. 85
15. The supporting member having a groove receiving a conductor held by the clamp. 90
6. In a car heater, a metallic supporting member mounted against the side of a car beneath a seat, longitudinally extending foot rests carried by said supporting member, a transverse member carried by said foot rests and extending through the seat pedestal, a support carried by the foot rests, a radiating member having one end secured to the first named support and its other end carried by the second named support, a heating unit within the radiating member, the first named support having a groove therein, a grounded conductor lying within said groove, and means carried by the first named support for holding the conductor within the groove. 95
20. The first named support having a groove therein, a grounded conductor lying within said groove, and means carried by the first named support for holding the conductor within the groove. 100
25. In a car heater, a metallic supporting member mounted against the side of a car beneath a seat, longitudinally extending foot rests carried by said supporting member, a transverse member carried by said foot rests and extending through the seat pedestal, a support carried by the foot rests, a radiating member having one end secured to the first named support and its other end carried by the second named support, a heating unit within the radiating member, the first named support having a groove therein, a grounded conductor lying within said groove, and means carried by the first named support for holding the conductor within the groove. 105
30. The first named support having a groove therein, a grounded conductor lying within said groove, and means carried by the first named support for holding the conductor within the groove. 110
35. In a car heater, a metallic supporting member mounted against the side of a car beneath a seat, longitudinally extending foot rests carried by said supporting member, a transverse member carried by said foot rests and extending through the seat pedestal, a support carried by the foot rests, a radiating member having one end secured to the first named support and its other end carried by the second named support, a heating unit within the radiating member, the first named support having a groove therein, a grounded conductor lying within said groove, and means carried by the first named support for holding the conductor within the groove. 115
40. The first named support having a groove therein, a grounded conductor lying within said groove, and means carried by the first named support for holding the conductor within the groove. 120
45. In a car heater, a metallic supporting member mounted against the side of a car beneath a seat, longitudinally extending foot rests carried by said supporting member, a transverse member carried by said foot rests and extending through the seat pedestal, a support carried by the foot rests, a radiating member having one end secured to the first named support and its other end carried by the second named support, a heating unit within the radiating member, the first named support having a groove therein, a grounded conductor lying within said groove, and means carried by the first named support for holding the conductor within the groove. 125
50. The first named support having a groove therein, a grounded conductor lying within said groove, and means carried by the first named support for holding the conductor within the groove. 130
55. In a car heater, a metallic supporting member mounted against the side of a car beneath a seat, longitudinally extending foot rests carried by said supporting member, a transverse member carried by said foot rests and extending through the seat pedestal, a support carried by the foot rests, a radiating member having one end secured to the first named support and its other end carried by the second named support, a heating unit within the radiating member, the first named support having a groove therein, a grounded conductor lying within said groove, and means carried by the first named support for holding the conductor within the groove. 135
60. The first named support having a groove therein, a grounded conductor lying within said groove, and means carried by the first named support for holding the conductor within the groove, the foot rests being slideable with respect to said transverse member to permit mounting of the member beneath seats of different lengths. 140
65. In a car heater, a metallic support disposable against the side of a car beneath a seat, foot rests carried by said support, a transverse member slideable along said foot rests and extending transversely through the seat pedestal, a transverse bar bridging and connected with the foot rests, a radiating member, a heating unit extending axially through the radiating member and projecting beyond both ends thereof with one end secured to the support and its other end supported by the bar. 145
70. The heating unit embodying a tubular metal case united to the radiating member. 150

GEORGE F. WENNAGEL. 145
CARROLL THOMAS.
